UNITED STATES PATENT OFFICE

WILBER J. PINE, OF OSHKOSH, WISCONSIN.

WIRE-INTERLACING MACHINE.

1,214,711.

Specification of Letters Patent.

Patented Feb. 6, 1917.

Application filed January 14, 1915. Serial No. 2,137.

To all whom it may concern:

Be it known that I, WILBER J. PINE, a citizen of the United States, residing at Oshkosh, county of Winnebago, and State 5 of Wisconsin, have invented new and useful Improvements in Wire-Interlacing Machines, of which the following is a specification.

My invention relates to improvements in 10 wire coiling, weaving or interlacing machines.

The objects of my invention are to provide efficient means for controlling the interlacing feeders, whereby their stroke may 15 be increased or diminished at pleasure to interlace one or more than one wire at any given time. Also to provide means whereby wire fabric of any desired width may be produced. Also to provide an improved 20 timing structure, whereby the length of the strand may be definitely determined. Also to provide other improvements, whereby machines of this type may be more efficiently controlled and operated, and whereby 25 one wire may be fed during one interlacing operation in alternation with another interlacing operation, wherein a plurality of wires are fed simultaneously.

In the drawings, Figure 1 is a plan view 30 of a machine embodying my invention, with the table partially broken away to disclose the interlacing wheels and a portion of the actuating and controlling mechanism. Fig. 2 is a side elevation of the same with the 35 end portions of the machine broken away. Fig. 3 is a front end elevation, showing the actuating and timing mechanism. Fig. 4 is a sectional view, drawn to a vertical plane cutting the axis of the wire feeding rolls 40 and roll supporting shafts. Fig. 5 is a sectional view, drawn on line α — α of Fig. 3. Fig. 6 is a detail plan view of the apparatus 45 for manually controlling the interlacing operation and cutting off the wire upon the completion of that operation. Fig. 7 is a detail view in elevation, showing a portion 50 of the actuating connections for the interlacing apparatus.

Like parts are identified by the same reference characters throughout the several views.

The operation of weaving or interlacing wire coils to form what is known as woven wire mattress fabric, is performed in my 55 improved machine in the following manner.

Wire withdrawn from a spool at 1, passes upwardly and over a guide pulley 2, and then between feeding rollers 3 and 4, the roller 4 being provided with a groove 5 of sufficient depth to partially receive the wire 50 without preventing it from being securely gripped by said feeding rollers. These rollers 3 and 4 force the wire through a coiling die 5', which may be assumed to be of any ordinary construction, provided with a helical groove or passage through which the wire is forced by the feeding rollers and thereby guided along a curved line, whereby the wire is helically coiled. The coil continues to rotate during the continuance of 65 the coiling operation resulting from its passage through the die 5'. After leaving the die, the coil passes through guide 6, over a set of guiding wheels 7, 8 and 9, which are disposed in diagonal planes across the line 70 of travel of the coil. These wheels are provided with projecting pins 10, and a partial rotation of the wheels in the direction indicated by the arrows in Fig. 1, shifts the fabric, *i. e.* the preceding coil or coils, laterally and angularly to a point where the extremity of the incoming coil will interlace 75 with one or more of the previously formed coils resting upon the surface of the table 80 11. The pins 10 not only position and hold 85 in position the previously formed coils, but other pins on the same wheel guide and hold the incoming coil in position to interlace therewith. The axes of the guiding wheels are preferably below the level of the table 90 11 and only the upper portions of the wheels project above the surface of the table 11, the table being provided with suitable diagonal slots through which these upper portions 95 of the wheels may project. This arrangement allows the peripheral projections or pins 10 to move diagonally along the surface of the table for a short distance and then downwardly through the slots. By locating the axial supports of the wheels below the table instead of above it, I am enabled 100 to get these supports and the actuating connections for the wheels out of the way underneath the table, where they will not interfere with an inspection of the interlacing operation nor with the coils themselves.

The guiding members 7, 8 and 9 may be actuated from an operating handle 20, which is axially rotatable and operatively connect- 110

ed to move with a cam disk 22, which is mounted to oscillate upon stud shaft 23 supported by bracket 21. Cam disk 22 is provided with an adjustable cam 24, which 5 comprises a bar having slots 25 therein and loosely secured to the under surface of the cam disk 22 by set screws 26. The adjustable cam or bar 24 extends tangentially to the hub 28 of the cam disk 22, and is provided on one end with a rounded surface 29. 10 When the handle 20 is swung to rotate the cam disk 22 in the direction indicated by the arrow, cam bar 24 will be brought into contact with a roller 31 carried by an elbow 15 crank 32, loosely mounted on shaft 33. The continued oscillatory movement of the cam disk 22 then causes cam projection 24 to push roller 31 backwardly and oscillate the elbow lever or bell crank 32, and this oscillatory movement will be transmitted to the 20 guiding members 7, 8 and 9, through link rod 35, lever 36, link 37, swinging arm 38, pawl 39, ratchet wheel 40, shaft 41, and pinions 42. The rotative movement of the 25 cam disk 22 is limited by mutually engaging stop projections 43 on the bracket, and 44, 44' on the disk.

Each of the pinions 42 is so located that teeth engage the projections or pins 10 on 30 one of the guiding wheels 7, 8 or 9, said projections being adapted to perform the function of gear teeth in addition to the function above described, of guiding the coils. It is therefore obvious that when the pinions 42 35 are rotated, as above described, their motion will be communicated to the guiding members or wheels 7, 8 and 9, and the degree of motion thus communicated, will ultimately depend upon the position of the adjustable cam or cam bar 24, since it is obvious that 40 when cam bar 24 has moved to a point where its rounded end 29 engages roller 31, it will cease to actuate said roller, since the rounded end 29 of the cam is curved in an arc described from the axis of shaft 23 as a center. 45

To vary the length of stroke of the elbow lever 32 and the consequent degree of movement transmitted to the guiding wheels 7, 8 and 9, I provide means whereby a rotary 50 movement of the handle 20 may be transmitted to shift the cam bar 24 tangentially of the hub 28, thereby causing the curved surface 29 to either move outwardly or recede from the position in which it is illustrated in Fig. 6. To accomplish this, a lever 55 45 is mounted to oscillate upon shaft 23. One end of this lever is loosely engaged in a socket 46 in the cam bar 24. The other end of this lever is provided with a segment 60 47. A shaft 49 extends radially along disk 22 through bracket 21' and is provided with a pinion 50 in mesh with said segment. The outer end of this shaft 49 extends into hand lever 20, which is provided with a disk 53, 65 which bears against a disk 52 rigid on the

bracket 21'. The disk 53 is provided with a pin 55, which is adapted to engage in any one of a series of sockets 56 in disk 52 to lock the disks 52 and 53 together. The handle 20 carries a key 60, which enters a key 70 way in shaft 49, which permits an axial movement of hand lever 20 on shaft 49. A coiled spring 58, within the handle, normally holds disk 53 against disk 52 with pin 55 interlocked. By retracting the handle 20, the key or pin 55 may be withdrawn from any socket 56 in which it is engaged, whereupon the handle, shaft 49 and pinion 50 may be rotated until the pin 55 is in position for registry with another socket 56, with which such pin may then be permitted to engage. During this rotative movement of the handle upon its axis, pinion 50 transmits motion through segment 47 and lever 45 to change the adjustment of the cam bar 24. Suitable gage marks will be employed, whereby the degree of this adjustment will be indicated on disks 52 and 53. A key 63, carried by bracket 21', and operating in a key-way 64 in shaft 49, locks shaft 49 against 80 axial movement.

After transmitting motion to the guiding members 7, 8 and 9, as above described, if the handle 20 is manually released, it swings back to normal position under the tension 95 of the spring 70. Elbow crank 32 and its connections through link rod 35, are independently returned to normal position by a coiled spring 71. The guiding members, however, remain in the position to which they have been rotated, since the retractive movement of elbow lever 32 is not transmitted to the ratchet wheel 40, pawl 39 retracting without actuating said ratchet wheel.

Cam disk 22 is provided with one or more depressions or notches 75 in its periphery, which are adapted to receive a roller 76 carried by a lever 77, rigidly connected with shaft 33. Shaft 33 extends upwardly 110 through the hub of bracket 34 and its upper end is connected with a lever 78, which carries a wire cutter 79. The wire cutter is normally in wire cutting position with reference to a shear bar 80, the latter also serving as a guide for the coil. When the operator starts to swing lever 20 to the left, and the initial movement of the lever rotates cam disk 22 to a position in which roller 76 is forced outwardly from the cam recess or 120 depression 75, this actuates lever 77 and transmits motion through shaft 33 to lever 78, thus severing the last previously formed coil or coils. The lever 20, in its limited movement, and through the several parts 125 herein described, performs all the functions of severing coils and moving the formed fabric into position to be engaged by the succeeding coil or coils. The adjustment of cam bar 29 determines the distance the 130

wheels 7, 8 and 9 shall rotate by each swing of lever 20 and thus determines the formation or pattern of the fabric, which is being woven, as it is obvious that by adjustment 5 of disk 53 above described, cam bar 29, as adjusted, gives a greater or less throw to the wheels 7, 8 and 9, and thus the wheels can be rotated a distance equal to the space or spaces between one, two, three or four pins 10 as predetermined by the preliminary rotative adjustment of the handle upon its own axis. When the operator releases lever 20 after a swinging operation, the latter swings back to normal position, whereupon roller 76 15 again registers with cam recess 75 and lever 77 returns to its normal position under the tension of springs 85, leaving the previously completed and now severed coil interlaced with the other coils on the table 11 and advanced 20 forwardly and laterally to a position where the next coil will interlace with it. The machine is now started to feed in the next coil, which will interlace with the coil or coils, thus pushed over and held in position 25 by the wheels 7, 8 and 9. The extremity of the new coil will not follow the curves of the preceding one, owing to the fact that the preceding coil has moved forwardly to a position where the extremity of the new coil 30 will cross its turns and pass through it during each successive rotation.

The coils on the table 11 may be of considerable length. In order that their parallelism may be maintained, I employ a bar 89 35 which is mounted upon the surface of table 11 and cooperates with the wheels 7, 8 and 9, in pushing the completed coils laterally. This bar is held in a parallel position and is moved laterally upon the table simultaneously 40 with the lateral movement imparted by the guiding rollers 7, 8 and 9, such motion being derived from the laterally projecting arm 32' of elbow lever 32. The motion of the arm 32' is transmitted to the bar 89 45 through link rod 91, lever 92, bar 93, and bell-cranks 94, connecting bar 93 at intervals with the guide bar 89. The coils also sometimes require to be steadied during the feeding operation. For this purpose I employ 50 a resilient guide 96, having a diagonal projection 97 and adapted to be manually adjusted into greater or less proximity to the rotative guiding member 9.

Power transmitting mechanism.—The 55 feeding-in rolls 3 and 4 are mounted upon shafts 100 and 101 respectively. Motion is transmitted from shaft 101 to the shaft 100 through gear wheels 102 and 103. Shaft 100 is mounted in bearings 105, which are resiliently supported by springs 106, which are suitably socketed in the frame. This allows a slight vertical yielding movement of shaft 100, which may be limited by screws 108, having threaded bearing cap plates 109, 60 within which the bearings 105 slide. Roller

3 may therefore be raised or lowered to increase or decrease the tension on the wire. The roller 3 is also provided with a peripheral ring *a* mounted upon an annular resilient cushion *b*, preferably formed of rubber, thereby allowing a slight yielding movement of the peripheral ring *a* and allowing the roller to accommodate itself to wire which varies in thickness in different portions thereof. 70

Shaft 101 is actuated from a driving pulley 112, which may be connected with the shaft by a clutch 113. The clutch operating lever 114 may be actuated to setting position by a cone 115, having sliding key connection 75 with shaft 101 and adapted to be shifted by the elbow crank shifting lever 117. To set the clutch, the lever 117 may be manually actuated from any suitable point, by means of a flexible wire or cable 118 (Fig. 1), 80 which extends over a pulley 119 and downwardly from said pulley with its lower end connected to a rod 120, extending from arm 117' of the elbow lever through slot 121 in the frame, as shown in Fig. 4. 85

When arm 117' has been raised, cone 115 will be shifted to actuate clutch setting arm 114, and the shifting lever 117 will be locked in this position by a latch 125 pivoted to the frame at 126, and having an upwardly projecting arm which provides a shoulder at 90 127 to be engaged by a projection 128 carried on the inner face of the arm 117' of the shifting lever. The latch yields during this upward movement to allow projection 128 100 to pass above the rest 127, after which the latch drops by gravity to a position in which it is shown in Fig. 3. When the shifting cone 115 is moved to clutch setting position, the machine may of course be actuated 105 through power applied through the pulley 112, and will continue in operation until latch 125 is actuated to swing the rest 127 out from underneath projection 128 to allow the retraction of the clutch setting cone 115. 110

The latch may be operated manually by means of a handle 130 pivoted to the frame at 131 and provided with an upwardly projecting arm 132, the motion of which is transmitted to the latch through link 133, 115 arm 134, shaft 135, and an arm 136 connected with said shaft and upon which the arm 129 of the latch normally rests. But it is desirable also to provide automatic timing mechanism, whereby the machine will be 120 automatically stopped after a given interval of operation, viz: the interval required to feed one length of coiled wire along the side of the fabric which is being formed. For this purpose I mount a rack bar 138 in the 125 frame and provide it with a projection 139, which, when the rack bar is moved to the right from the position indicated in Fig. 3, will contact with the angularly disposed under surface of latch arm 129 and raise the 130

latch to releasing position. Rack bar 138 is so actuated from shaft 101 through a worm 140 carried thereby, worm wheel 141, clutch 142 (Fig. 5), and pinion 143, the teeth of the latter being in mesh with those of the rack 138. The clutch 142 is a cone clutch, adapted to engage within the rim of the worm wheel 141. A coiled spring 150, socketed in a slotted stud shaft 151, within the hub of the worm wheel, tends to push the clutch 142 to retracted position, but the clutch may be held in motion transmitting position by a set of expander rings 156 and 157 (Fig. 1), which are mounted between a head 158 on stud shaft 151, and a collar 160 keyed to slide on shaft 151 and bearing against clutch hub 142 on which pinion 143 is mounted. The expander rings 156 and 157 have abutting cam surfaces with a shoulder at 161, and ring 157 has a projecting operating arm 162, whereby it may be rotated relatively upon ring 156, which has sliding key connection with shaft 151. The movement of the shoulder 161 upon the corresponding shoulder or cam projection 163 of ring 156, causes a separation of said rings, thereby forcing the pinion 143 and clutch 142 inwardly until clutch member 142 engages worm wheel 141.

The operating arm 162 of the expander is resiliently connected with arm 117' of the clutch setting lever, a coiled spring 167 being preferably employed. Therefore when the parts are in the position shown in Fig. 3, worm wheel clutch 142 will be retracted, but if arm 117' is lifted by a pull upon the wire 118 to shift clutch operating cone 115 and set the main clutch 113, motion will be simultaneously communicated from arm 117' to expander arm 162, lifting the latter and rotating expander ring 157 relatively to ring 156, thereby setting the worm clutch 142. When the machine is set in operation, motion will be transmitted from shaft 101, through the worm 140, worm wheel 141, and the worm clutch 142, to actuate pinion 143, the latter being fast on the hub 170 of clutch member 142. The rotation of pinion 143 will move the rack bar 138 to the right from the position in which it is shown in Fig. 3, until projection 139 engages and lifts latch arm 129, whereupon elbow crank 117 is permitted to withdraw cone 115 from its operative relation to the cone clutch. During this movement, the downward movement of arm 117' carries with it expander arm 162. The initial movement of the latter releases worm clutch 142 and allows it to be pushed out of operative position by spring 150. The clutch 142 having been rotated against action of spring 149, as soon as released will return to normal and with it rack bar 138 is through reverse action of pinion 143, returned to normal and to the position in which it is illustrated in Fig. 3. The lever

117 will now be retracted by spring 169 to withdraw cone 115. The machine will now stop and remain at rest until it is again started by pulling upon the wire 118, thereby setting the main clutch.

Multiple feeding mechanism.—Where more than one strand of wire is to be fed at a time, I employ additional feeding rollers 175 and 176 respectively. The construction and arrangement of these rollers is substantially identical with that of the rollers 3 and 4, and they will therefore not be described in detail. They are operatively connected with these shafts 100 and 101 by keys 180, each of which may be actuated by a knob 181 into and out of motion transmitting relation to the roller 175 (or 176). When the knobs are pushed inwardly, as shown in Fig. 4, these rollers 175 and 176 will be loosely supported and therefore inoperative for feeding wire, but by pulling the knobs outwardly, they will be connected with the respective shafts for motion transmission. There will of course be as many coiling dies 5 as there are sets of feeding rollers, and where more than one strand of wire is fed, the several strands will be received between successive pins or projections 10 on the guiding members 7, 8 and 9. These guiding members will be rotated a greater distance where two sets of wire are being simultaneously fed, than will be the case where only one wire is fed. This additional movement, however, can be readily provided for by shifting adjustable cam bar 24 on disk 22.

I claim—

1. A wire interlacing machine, including the combination with means for rotating and axially advancing a coil of wire, of a rotatable guiding member adapted to bear against the coil, said member being rotatable in a plane diagonal to the line of advancement of the coil.

2. A wire interlacing machine, including the combination with means for rotating and axially advancing a coil of wire, of a rotatable guiding member located in a plane diagonal to the axis of the coil, said guiding member having a circular periphery provided with projections between which the wire of the coil may pass, substantially as described.

3. A wire interlacing machine, including the combination with means for rotating and axially advancing a coil of wire, of a rotatable guiding member adapted to move against and push the coil along a line diagonal to its line of advancement, and means for manually actuating said guiding member in step by step rotative movements.

4. A wire interlacing machine, including the combination with means for rotating and axially advancing a coil of wire, of a rotatable guiding member adapted to bear

- against the coil at an angle to its line of advancement, means for manually actuating said guiding member in step by step rotative movements, and means for shifting a portion of the actuating means to vary the length of the individual steps independently of the manual actuating operation. 5
5. A wire interlacing machine, including the combination with means for rotating and axially advancing a coil of wire, of a guiding member rotatable in a plane diagonal to the axis of the coil and adapted to push the coil along a line diagonal to its line of advancement, and means coöperative with the guiding member for maintaining a parallel relation between the interlaced coils and the interlacing coil. 10
6. A wire interlacing machine, including the combination with means for rotating and axially advancing a coil of wire, of a rotatable guiding member adapted to bear against the coil at an angle to its line of advancement, and means for manually actuating said guiding member in step-by-step rotative movements, said actuating means including a rotatively adjustable handle adapted in any given position of rotative adjustment, to automatically determine the length of the step-by-step movements. 20
- 25 7. A wire interlacing machine, including the combination with means for rotating and simultaneously advancing a coil of wire, of a rotatable guiding member, means for actuating the same in step-by-step adjustments, a spring retracted wire cutter, means connected with the step-by-step mechanism for actuating the wire cutter for a cutting operation. 30
- 35 8. A wire interlacing machine, including a rotative coil guiding member provided with peripheral projections in combination with means for feeding coils of wire between said projections along a line diagonal to the plane of rotation of said member. 40
- 45 9. A wire interlacing machine, including the combination with a wire supporting table, provided with a set of slots, of a set of rotative guiding members axially supported below the table and having peripheral portions extending through the slots, projections on the peripheral portions of said members adapted to loosely engage a coil of wire, and means for feeding coils of wire diagonally across said slots. 50
- 55 10. A wire interlacing machine, including the combination with a coil-supporting table, means for feeding coils of wire along one margin thereof, said marginal portion of the table having a diagonal slot, of a 60 rotative guiding member having wire-engaging projections projecting through said slot, and adapted, when the guiding member is actuated, to shift an engaged coil of wire diagonally to its line of feed upon said table. 65
11. A wire interlacing machine, including the combination with wire guiding devices, of a manually actuated rotative member, a motion transmitting cam thereon, and means for transmitting the movement of the cam to the guiding devices. 70
12. A wire interlacing machine, including the combination with wire guiding devices, of a manually actuated rotative member, a motion transmitting cam thereon, and means for transmitting the movement of the cam to the guiding devices, said cam being adjustable upon said rotative member to vary the degree of motion transmission. 75
13. A wire interlacing machine, including the combination with an oscillatory controlling member, of a cam adjustably mounted thereon, and an axially rotative handle for said member provided with connections for utilizing rotative movements of the handle to adjust the cam. 80
14. A wire interlacing machine, including the combination with an oscillatory controlling member, of a set of coil guiding devices operatively connected with the controlling member, a paralleling bar coöperating with said guiding devices, parallel motion mechanism for actuating said bar, and operating connections between the parallel motion mechanism and the controlling member. 90
15. A wire interlacing machine, including the combination with an oscillatory controlling member, of a set of coil guiding devices operatively connected with the controlling member, a paralleling bar coöperating with said guiding devices, parallel motion mechanism for actuating said bar, operating connections between the parallel motion mechanism and the controlling member, and means for adjusting said controlling member to automatically change the degree of movement transmitted to the guiding devices and paralleling bar. 100
16. A wire interlacing machine, including the combination with a coil-supporting table provided with a set of diagonal slots therein, a set of wire guiding wheels journaled underneath said table and each projecting through one of said slots, a motion transmitting shaft provided with a set of wheels each in driving connection with one of the guiding wheels, an operating lever, and connections for imparting rotative movements of definite length to the shaft when said lever is actuated. 110
17. A wire interlacing machine, the combination with a coil-supporting table provided with a set of diagonal slots, a motion transmitting shaft underneath said table in diagonal relation to said slots, a set of wire-guiding wheels journaled underneath said table and projecting through said slots above the upper surface thereof, wire-engaging 125
- 130

projections on said wheels, gear wheels on said shaft having teeth with which the projections on said guiding wheels intermesh, and means for manually rotating said shaft 5 in a series of step-by-step movements of definite length.

18. A wire interlacing machine, including a spring-actuated motion-transmitting member, an oscillatory actuating member, a 10 cam adjustably mounted thereon, and adapted to engage said motion-transmitting member and force the same outwardly from the axis of said oscillatory member when said member is oscillated, a set of coil-guiding 15 members, and connections between said motion-transmitting member and said guiding devices.

19. A wire interlacing machine, including wire coiling and guiding members and a 20 coil-supporting table, in combination with a diagonally disposed resiliently supported steadyng member mounted upon the table, and adapted to be manually actuated against the moving coil.

25. 20. A wire interlacing machine, including wire feeding mechanism comprising plural sets of wire feeding rollers, driving shafts upon which the opposing rollers of each set are mounted, and means for disengaging the 30 driving connections to both rollers of one set whereby the feeding operation of said set may be discontinued without disengaging the rollers from the wire, the other rollers remaining in operation.

35. 21. A wire interlacing machine, including timing mechanism, comprising the combination with a main shaft, and a clutch for connecting the same with a source of power, of clutch setting mechanism, a trip latch to 40 hold said mechanism in clutch setting position, a worm actuated from said main shaft, a worm wheel in mesh therewith, and pinion and rack mechanism for transmitting motion from the worm wheel to actuate the trip latch after the rack has moved a predetermined distance.

22. A wire interlacing machine, including timing mechanism, comprising the combination with a main shaft, and a clutch for connecting the same with a source of power, of clutch setting mechanism, a trip latch to hold 45 said mechanism in clutch setting position, a worm actuated from said main shaft, a worm wheel in mesh therewith, and pinion and rack mechanism for transmitting motion from the worm wheel to actuate the trip latch after the rack has moved a predetermined distance, said rack having a projec-

tion to engage and release the trip latch during the final movement of the rack. 60

23. A wire interlacing machine, including timing mechanism, comprising the combination with a main shaft, and a clutch for connecting the same with a source of power, of clutch setting mechanism, a trip latch to hold 65 said mechanism in clutch setting position, a worm actuated from said main shaft, a worm wheel in mesh therewith, and pinion and rack mechanism for transmitting motion from the worm wheel to actuate the trip 70 latch after the rack has moved a predetermined distance, and resetting connections adapted to automatically restore the rack to normal position independently of the worm wheel, when the clutch mechanism is again 75 actuated to reset the main clutch.

24. A wire interlacing machine, including timing mechanism, comprising the combination with the moving parts of the machine, of a worm adapted to be actuated thereby, a 80 worm-wheel, a trip-latch operatively connected with the worm-wheel and controlling the driving connections of the machine, and manual resetting connections for the trip-latch and driving connections. 85

25. A timing mechanism for wire interlacing machines, including the combination of a lever controlling the operation of the machine, a trip-latch for holding said lever in a position permitting machine operation, 90 a slide adapted to release said trip-latch after a predetermined movement, and means, connected with the moving parts of the machine, for actuating said slide.

26. A timing mechanism for wire interlacing machines, including the combination of a lever controlling the operation of the machine, a trip-latch for holding said lever in a position permitting machine operation, 95 a slide adapted to release said trip-latch after a predetermined movement, and means, connected with the moving parts of the machine, for actuating said slide, together with means for manually resetting the controlling lever, and connections for utilizing the resetting movement of said lever to restore the slide to normal position and adjust the slide-operating mechanism for a subsequent trip-releasing movement. 100

In testimony whereof I affix my signature 105 in the presence of two witnesses.

WILBER J. PINE.
